UNITED STATES PATENT OFFICE.

CLAUDE N. BIELENBERG AND ALBERT E. ROBISON, OF DEER LODGE, MONTANA.

ORE CONCENTRATOR.

Application filed November 26, 1923. Serial No. 677,087.

To all whom it may concern:

Be it known that we, CLAUDE N. BIELENBERG and ALBERT E. ROBISON, citizens of the United States, residing at Deer Lodge, 5 in the county of Powell and State of Montana, have invented certain new and useful Improvements in Ore Concentrators, of which the following is a specification.

This invention relates to ore concentrators 10 of that type wherein the separation of the values or heavier metal particles and the gangue or lighter constituents from the ore is effected by the combined action of a washing operation and an agitating operation.

15 The primary object of the invention is to generally simplify and improve ore concentrators of the above kind whereby the same will be rendered extremely effective in operation and will be simple and durable in 20 construction.

Another object of the invention is to provide an ore concentrator embodying an elongated shaking box or table in the general form of a trough provided with baffling 25 plates, and means for adjusting the distance between said plates and the bottom of the box or table whereby the box may be effectively operated in connection with ore of varying coarseness.

30 Still another object of the invention is to provide the adjustable slides with horizontal baffling boards whereby maintenance of the heavier metal particles at the bottom of the box or table will be insured, provision being 35 made by a peculiar construction of the sides of the box for facilitating the flow of the gangue over the sides of the box to a desired point of disposal.

Still another object of the invention is to 40 provide a novel and improved arrangement of washing means whereby the ore will be subjected to jets of water in the shaking table or box for effectively breaking up and dissolving the ore constituents, so that the 45 values will readily separate therefrom.

Other objects will appear as the nature of the invention is better understood, and the same consists in the novel form, combination, and arrangement of parts hereinafter 50 more fully described, shown in the accompanying drawing and claimed.

In the drawings wherein like reference characters indicate corresponding parts throughout the several views:

55 Figure 1 is a top plan view of an ore

concentrator constructed in accordance with the present invention.

Figure 2 is a longitudinal sectional view thereof, taken substantially upon the line 2-2 of Figure 1.

Figure 3 is an enlarged transverse sectional view, taken upon the line 3-3 of Figure 1, and

Figure 4 is an elevational view of one of the baffling slides and its attached horizontal 65 baffling plate or board.

Referring more in detail to the drawings, the present invention consists of an elongated open top box including side walls 5 having longitudinal grooves in the inner faces 70 thereof adjacent their lower edges, in which the opposite longitudinal edges of a bottom wall 6 snugly fit, and the walls 7 and 8 being provided between the side walls 5 with their side edges disposed in vertical grooves 75 in the adjacent faces of the walls 5 as shown clearly in Figure 1, the end walls 7 and 8 being provided with grooves in the inner faces thereof, near their lower ends in which the ends of the bottom walls 6 are seated, 80 and tie bolts 9 being provided between the projecting ends of the side walls 5 outwardly of the end walls 7 and 8 for securing the several walls of the box construction rigidly 85 assembled.

The box thus constructed is gradually reduced in depth from its intake end at the end walls 7 to its discharge end at the end wall 8, by providing inclined upper edges on the side walls 5 and forming the end wall 90 8 of shorter size than the end wall 7. The box also tapers narrower in width toward its outlet end by providing converging side edges on the bottom wall 6 as shown clearly in Figure 1, and the interior of this box is 95 divided into a plurality of successively smaller compartments by means of a plurality of vertical substantially uniformly spaced slides 10 whereby compartments are provided which vary in size according to the 100 sizes of the values concentrated or collected in the bottoms of said compartments.

The side walls 5 are provided with aligned pairs of vertical slots in their inner faces in which the opposite side edges of the slides 10 project, whereby said slides are effectively guided for vertical movement, and any suitable means, such as screws 11 may be provided for regulating the distance between the upper surface of the bottom wall 6 110

and the lower edges of each of said slides. In the construction shown, each slide 10 is provided with an internally threaded boss 12, at each side of the same and at the upper end thereof, through which the screws 11 are threaded, and whereby the said screws are positioned to bear upon the upper edges of the side walls 5 for effecting the above mentioned adjustment.

16. Suitably rigidly secured to the lower end of the slide 10 are horizontal baffling boards 12 that project toward the outlet end of the box and which act to keep the metallic particles in the box. In order to facilitate flow 15 of the gangue over the sides of the box, behind each of the slides 10, the upper edges of the side walls 5 are notched or cut away at diametrically opposed points as indicated at 13.

20. The ore washing device of the construction consists of a pair of longitudinal nozzle pipes 14 that are seated within grooves provided in the upper surfaces of the bottom walls 6 and the side edges thereof and in 25 the inner faces of the side walls 5, said pipes or notches being provided with a longitudinal series of openings at 15 upon their inner sides and substantially flush with the upper surface of the bottom wall 6; so that 30 when water is supplied under pressure to the pipes 14, the same will flow inwardly in opposite directions and transversely of the box in relatively strong jets, whereby the ore will be effectively dissolved and washed 35 with respect to certain constituents thereof, it being noted that the flow longitudinally of the box is induced, due to the gradually reduced depth of the same. The ends of the nozzles or pipes 14 may be connected to a 40 common manifold pipe 16 at the intake or higher end of the box, which manifold is connected with a suitable supply pipe 17 having a control valve 18. The depth of the pipes 14 at the shallower or outlet end 45 of the box are closed by suitable means such as caps as indicated at 19, and the table or box is adapted to be laterally reciprocated or given a jiggling movement through the medium of suitable mechanisms well known 50 in the art. Such means is diagrammatically shown as consisting of a power shaft 20 having end cranks 21 connected with one of the side walls 5 through the medium of links 22.

55. In operation, the ore is deposited within the larger end compartment of the box at the deeper end of the latter and the valve 18 is opened for permitting the water to flow through the openings 15 in a plurality 60 of strong jets transversely of and across

the upper surface of the bottom wall 6, it being understood that the gates or slide valves 10 have been previously adjusted to the required height in accordance with the material to be handled. The action of the 65 water impinging against the ore tends to dissolve the gangue so that the same may rise to the top of the water and flow over the top edges of the side walls 5, particularly at the notches 19. The coarser metal 70 will be retained within the larger end compartment and the successive compartments will retain the values in accordance with the sizes thereof and the different adjustments of the several slides 10. Also, the baffling 75 boards 12 while permitting the lighter constituents to rise and overflow at the notches 19 will effectively tend to keep the heavier particles or metals within the box below said notches 19. The concentrated metals 80 may be recovered from the several compartments in any preferred or well known manner.

An ore concentrator constructed in accordance with the above will be found to 85 operate with extreme efficiency and may be constructed and operated at a comparatively small cost, and provides a structure which will be extremely durable.

What I claim as new is:

1. In an ore concentrator, an elongated box having means for reciprocating the same laterally, said box including side, end and bottom walls, and opposed longitudinal water pipes disposed at the juncture of the 90 inner surfaces of the bottom wall and side walls and having longitudinal series of jet openings in the inner sides thereof through which water may pass in jets travelling inwardly toward each other across the upper 95 surface of said bottom wall.

2. In an ore concentrator, an elongated box including end, side and bottom walls, the upper edges of said side walls inclining from one end toward the other whereby the 100 depth of the box is gradually increased from the intake to the outlet ends thereof, vertically adjustable slides arranged in spaced parallel relation between the side walls and extending transversely of the box, 105 said side walls having notches in the upper edges thereof at the rear sides of each of said slides, and horizontal baffling boards rigid with the lower ends of the slides and extending from the latter toward the outlet 110 ends of the box.

In testimony whereof we affix our signatures.

CLAUDE N. BIELENBERG.
ALBERT E. ROBISON.
